UNITED STATES PATENT OFFICE.

EDWIN G. STAUDE, OF MINNEAPOLIS, MINNESOTA, ASSIGNOR TO E. G. STAUDE MANUFACTURING CO., OF MINNEAPOLIS, MINNESOTA, A CORPORATION.

PAPER-BOX-TOPPING MACHINE.

1,163,043.

Specification of Letters Patent.

Patented Dec. 7, 1915.

Application filed November 4, 1912. Serial No. 729,427.

To all whom it may concern:

Be it known that I, EDWIN G. STAUDE, a citizen of the United States, and resident of Minneapolis, in the county of Hennepin, 5 State of Minnesota, have invented certain new and useful Improvements in Paper-Box-Topping Machines, of which the following is a specification.

The object of my invention is to improve 10 the machine shown and described in my pending application, Serial No. 711,001, filed July 22, 1912. In this machine I have found it difficult to gum the label and then place it smoothly and evenly on the top of the 15 box cover. The label is usually made of thin paper and I have found it had a tendency to wrinkle, particularly after it had been moistened by the application of the glue thereto.

20 My present invention contemplates the elimination of this difficulty and objection by the application of the glue to the cover itself and then applying the dry label to the glued surface of the cover.

25 The invention consists generally in various constructions and combinations, all as hereinafter described and particularly pointed out in the claims.

In the accompanying drawings forming 30 part of this specification, Figure 1 is a plan view of a paper box topping machine embodying my invention, Fig. 2 is a longitudinal, vertical, sectional view of the same, Fig. 3 is a transverse sectional view taken 35 on the line $w-w$ of Fig. 2, Fig. 4 is a detail sectional view, showing the mechanism for applying the glue to the surface of the cover, Fig. 5 is a detail sectional view, showing the means for gripping the label and pressing 40 it on the surface of the cover, Fig. 6 is a similar view, showing the mechanism in the act of applying the label to the cover, the gripping means being released, Fig. 7 is a detail sectional view on the line $y-y$ 45 of Fig. 8, Fig. 8 is a sectional view on the line $x-x$ of Fig. 7.

In the drawing, 2 represents a suitable 50 frame, in which the operating mechanism of the machine is mounted. The side rails of the frame on one side of the machine are

provided with inwardly projecting lugs 3 and 4, preferably integral with the frame and having bearings for upright screw shafts 5. (See Figs. 2 and 3.) On these screw shafts yokes 6 are mounted and arranged to project into the space between the side rails of the frame, as shown in Fig. 3, and provided with bearings for parallel transverse shafts 7. At the upper ends of the screws 5 I provide beveled pinions 9 meshing with similar pinions 10 on a horizontal shaft 11 having an operating wheel 12 at one end of the machine. By revolving this shaft 11 the screw shafts 5, (of which I prefer to provide three in this machine) 65 will be operated simultaneously to raise or lower the yokes 6 and the transverse shafts 7. The yokes are connected with one another, preferably by horizontal parallel rods 13 and 14, and these rods are connected with 70 one another by transverse shafts 15. Brackets 16 and 17 have clamps 18 slidable on said shafts and locked thereon by means of screw wheels 19, and upon these brackets angle bars 20 are supported in parallel relation 75 with one another to form guide-ways for the moving box covers. These brackets 16 and 17 may be adjusted toward or from one another transversely of the machine to adapt the guide-ways for different widths of box 80 covers.

At one end of the machine a hopper 21 is provided, in which the box covers are placed, one upon another, with depending flanges. The hopper is open at the bottom, as indicated in Figs. 2 and 3, and a sprocket belt 22, having pins 23 thereon, is mounted to operate beneath the hopper, the pins successively engaging the forward flange of the lower cover and drawing it out from 90 beneath the pile of covers. The sprocket belt operates over sprocket wheels 24 mounted on the shafts 7, the middle portion of the belt being held against the cover by a guide 26 mounted in brackets 27 which are 95 also adjustable on the shafts 15 transversely of the machine. The boxes are held down on the guide-ways by suitable means, such as bars 28 having pins 29 which are vertically adjustable in clamps 30 adjustably 100

mounted on a transverse shaft 31. In the operation of the machine, the covers will be fed, one at a time, from the hopper by the movement of the sprocket belt.

- 5   Mounted in bearings near the middle portion of the machine is a shaft 32 on which a cylinder 33 is secured. This cylinder has a series of longitudinal dovetailed slots 34 arranged at intervals in its periphery. A 10 curved plate 35 is adapted to fit the surface of the cylinder and is provided with a series of bolts 36 to slip into the slots in the surface of the cylinder. The heads of these bolts are counter-sunk in the plate 35 and when tightened will lock the curved plate firmly to the surface of the cylinder. Beneath the shaft 32 is a shaft 37 on which a series of segmental sections 38 are keyed, said sections having projecting points or toes 39 which 15 are adapted to engage the forward flange of the box cover and feed it beneath the cylinder 33. A second series of segmental sections 40 is provided, having curved slots 41 in their hubs to allow for rotary adjustment 20 of these sections on the shaft 37, the adjustment being limited by the engagement of the shaft key with the ends of the slots. The hubs of these sections are also provided with teeth 42 adapted to mesh with a pinion 43 25 mounted on a shaft 44 having a squared outer end 44^a (see Figs. 7 and 8) to receive a wrench or other tool, for the purpose of rotating the sections 40 and changing the relative position of these sections and the 30 section 38.

A gluing roll 48 is mounted in bearings above the glue pot 49 and is adapted to contact with the surface of the plate 35 and also with a roll 50 which is mounted on the 40 walls of the glue pot and partially immersed in the glue therein. As the cylinder 33 revolves, the roll 48 will contact with the plate 35 and will be out of contact with the portion of the cylinder surface not covered by 45 the plate 35. This plate can be readily removed for the insertion of another one in the cylinder to adapt the gluing mechanism for covers of different length or width. A scraper plate 51 is preferably mounted on 50 the glue pot, having an adjusting device 52.

Above the gluing mechanism I provide a label feeder, consisting of a hopper 53 and feed wheels 54 mounted in brackets 55. A roll 56 is provided below the feed wheels 55 having belts 57 between which and the feed wheels the labels are fed. The feed belts extend downwardly and are supported by a comparatively small roll 58.

Near the discharge end of the feed belts 60 I arrange shafts 59 and 60, one above another. On the upper shaft is a roll 61 having a recess 62 in its spherical surface in which a rock shaft 63 is arranged, carrying a series of spring-pressed grippers 64.

A stationary cam 65 is loosely mounted 65 on the shaft 59 and the rock shaft 63 is provided with an arm 66 to ride on the face of the cam. Normally the grippers will lie within the recess in the roll 61, as indicated in Fig. 5, the arm 66 riding on the high part 70 of the cam. As soon, however, as the arm reaches the low part of the cam the grippers will be forced outwardly by the spring 67 and will grip the label as it is fed down between the roll 61 and a comparatively 75 small roll 68. Spring guards 69 are provided to hold the forward portion of the label on the roll 68 until the grippers, operating between the guards, have engaged the label.

Upon the shaft 60 I arrange a series of segmental sections and operating means therefor corresponding to those shown and described with reference to Fig. 4, and I will designate these sections by the same reference numerals with the addition of the exponent "a," and I will now describe certain means for locking the segments on the shaft and common to both the shaft 60 and the shaft 37, but illustrated in Fig. 8 in connection with only the shaft 60. It will be understood, however, that the same mechanism is employed in the segmental roll beneath the gluing roll 33.

45^a represents heads mounted on the shaft 60.

46^a is an exteriorly threaded collar and 47^a an interiorly threaded lock nut engaging the threads of said collar and by means of which the adjacent head 45^a can be moved inwardly to clamp the segmental sections against the opposite stationary head 45^a. Between the segmental sections I prefer to provide collars 47' which are readily removable when the sections are released to allow for the proper adjustment and spacing of the sections to adapt them for box covers of different width. Whenever it is desired to change the adjustment of the sections to adapt the feeding device for box covers of 100 different length, the lock nut 47^a is loosened and then by means of the pinion 43^a the segments 40^a can be adjusted to increase or decrease the peripheral bearing surface for 105 the box covers.

The movement of the roll 61 and the sections 38^a will be so timed that the forward end of the box cover will register with the forward end of a label and just before the label contacts with the forward end of the 110 cover the grippers will release the label and will be swung back to their normal position within the recess 62. The passage of the label and cover will then continue and as the label is laid upon the cover surface it 115 will be pressed snugly against it by the peripheries of the roll 61 and the sections 38^a and 40^a and when the cover has been dis-

charged it will drop upon an inclined plate 70 with the label smoothly and evenly glued to the cover surface.

In the operation of the machine, the 5 covers are piled one upon another in the hopper and a quantity of labels are placed in the label hopper, the engagement of the lugs 23 with the forward flange of the bottom cover will feed it out from the hopper 10 and advance it to the position shown in Fig. 2. At this point the lug will move out of engagement with the cover flange and the cover will remain stationary until the second one comes along and pushes the foremost one into the gluing mechanism. This 15 movement will be continued through the machine, the succeeding covers feeding the foremost one to the gluing mechanism and to the label applying roll. The lower shaft 20 60 has a driven pulley 71 thereon and drives the upper shaft 59 through gears 72. A shaft 73 is geared to the shaft 60 and also to the shaft 37 of the gluing roll, which in turn is geared to the rolls 48 and 50. The 25 roll 56 is driven through a belt 74 from the shaft 60 and the feed belt 22 for the box covers is driven through a belt 75 from the shaft 37. I prefer also to provide hand 30 wheels 76 and 77 on the shafts 60 and 37 for convenience in adjusting the rolls in their proper relative position with respect to the segmental sections beneath, and thereby properly time the movement of these rolls to the travel of the box covers and the labels. 35 In various ways the details of construction may be modified and still be within the scope of my invention.

I claim as my invention:—

1. The combination, with means for feeding a cover, of a gluing roll, a curved plate mounted to fit the peripheral surface of said roll and adapted to apply glue to the top of the cover, said plate being removable to allow the substitution of other plates of varying sizes to adapt the gluing roll to the different sizes of covers, and means mounted in said plate and engaging slots in said roll for securing said roll and plate together.

2. The combination, with a box cover feeding means, of a gluing roll adapted to apply glue to the top of the cover and revolving means to engage the forward flange of the cover and feed it past said gluing roll.

55 3. The combination, with means for feeding a flexible box cover, of means for applying glue to the upper surface of said cover, and a roll composed of segmental sections adapted to engage and support said cover and feed it past said gluing roll.

4. The combination, with a hopper adapted to contain a series of box covers placed one upon another therein, of a feed belt having means to engage the forward flange of

the lower cover and advance it out of said 65 hopper, the engaging means of said feed belt passing out of contact with said cover at a predetermined point in its movement, the forward cover being engaged and pushed forward by contact of the succeeding cover 70 therewith, a gluing roll adapted to apply glue to the upper surface of the cover, and means arranged to engage the forward flange of said cover and move it past said gluing roll.

75 5. The combination, with a frame, of upright screw shafts journaled therein, a horizontal shaft having an operating wheel geared to the upper ends of said screw shafts for operating all of them simultaneously, yokes mounted on said upright screw shafts, parallel rods supported by said yokes, transverse shafts arranged between said rods and upright brackets mounted on said transverse shafts and having guide- 80 ways thereon.

6. The combination, with means for feeding a flexible box cover having flanged edges, said means engaging the inner face of the cover flange, of means for applying 90 glue to the upper surface of said cover.

7. The combination, with means for feeding a flexible box cover having flanged edges, said means engaging the inner face of the cover flange, of means for applying 95 glue to the upper surface of said cover, said feeding means forming a non-yielding support for said cover during the application of the glue to the upper surface thereof.

8. The combination, with means for feeding a flexible box cover having flanged edges, of means for applying glue to the upper surface of said cover, means contacting with the under surface of said cover and forming a support therefor during the 105 gluing operation, said support having recesses to receive said flanged edges.

9. The combination, with a box cover feeding means, of a gluing roll having a peripheral plate fitting snugly on the surface 110 thereof for applying glue to the upper surface of said cover, said plate having bolts thereon fitting within longitudinal slots in said roll.

10. The combination, with means for 115 feeding a flexible box cover, of a gluing roll for applying glue to the upper surface of said cover, means contacting with the under surface of said cover to form a rigid support therefor during the gluing operation, 120 said means having a toe for engaging the inner face of the cover flange to feed the same.

11. The combination, with means for feeding a box cover, of a gluing device, and a roll composed of segmental sections adapted to engage said cover and feed it past said gluing device.

12. The combination, with means for

feeding a box cover having flanged edges, of a gluing device, a roll composed of segmental sections adapted to engage a flange of said cover and feed it past said gluing device.

13. The combination, with means for feeding a box cover, of a gluing device, a roll composed of segmental sections adapted to engage and feed said cover, and means

for shifting the position of said segmental sections on the axis of said roll.

In witness whereof, I have hereunto set my hand this 29th day of October, 1912.

EDWIN G. STAUDE.
